[57] CLAIM

The ornamental design for a housing for an optical data reader, as shown and described.

DESCRIPTION

FIG. 1 is a top plan view of a housing for an optical data reader showing our new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a sectional view taken along line 6—6 of FIG. 1; and,

FIG. 7 is a sectional view taken along line 7—7 of FIG. 2.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : D 359,040
DATED : June 6, 1995
INVENTOR(S) : Nakamura, et al

It is certified that error appears in the above-identified patent and that said Letters Patent is hereby corrected as shown below:

On the title page item [75], "Yosimutu Sibata"
to --Yosimitu Sibata--.

Signed and Sealed this
Twenty-ninth Day of August, 1995
